UNITED STATES PATENT OFFICE

ALBERT P. GILBERT, OF THIENSVILLE, WISCONSIN, ASSIGNOR TO THE GILBERT SHOE CO., OF THIENSVILLE, WISCONSIN

SHOE CONSTRUCTION

Application filed April 18, 1932. Serial No. 605,903.

This invention pertains to a shoe construction embodying a one-piece rear quarter, and the method of manufacturing the same.

Heretofore many attempts have been made to construct a shoe of the foregoing character.

However, in this numerous difficulties have been encountered, both in the finished product and the process of manufacture. Therefore, shoes of this type have never proven to be popular or practical.

For instance, an inherent difficulty encountered in manufacture has been the inability to take care of excess material which accumulates below the heel seat in the lasting operation. This problem does not exist in two piece quarters, seamed at the rear, inasmuch as the same can be shaped to eliminate excess material.

Further, in attempting to provide a one-piece quarter, so shaped as to eliminate excess material below the heel seat, it was found that the top of the quarter could not be retracted or shaped to properly engage the ankle.

Various objections have resulted, all of which the present invention aims to overcome by the provision of a shoe having a one-piece quarter, so formed with relation to the lining as to avoid bunching of material below the heel seat, and provide a snug fit of the upper surrounding the ankle.

Incidental to the foregoing, a more specific object is to provide a tackless shoe, in which the upper, including a one-piece rear quarter, is stitched to the insole around its entire peripheral edge, including the heel seat, thus eliminating the usual tacks at the heel seat.

A further object resides in an improved method of manufacture, particularly with reference to forming the rear quarter, and the lasting and inseaming of the same.

A still further object in connection with the foregoing resides in the novel manner of forming and assembling the heel counter.

With the above and other objects in view, which will appear as the description proceeds, the invention resides in the novel construction, combination and arrangement of parts, substantially as hereinafter described, and

more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:—

Figure 1 illustrates the blank comprising a one-piece rear quarter constructed in accordance with the present invention.

Figure 2 illustrates the lining blank, with the quarter indicated thereon in dotted lines to illustrate the difference in contour.

Figure 3 is a perspective view of the quarter and lining assembled.

Figure 4 is a fragmentary elevation of an upper before lasting, and comprising a one-piece quarter constructed in accordance with the present invention.

Figure 5 is a fragmentary bottom plan view showing the upper and insole after lasting.

Figure 6 is a fragmentary side elevation illustrating the same.

Figure 7 is a fragmentary longitudinal section through a rear quarter, after the same has been lasted and inseamed to the inner sole, and

Figure 8 is a rear elevation of a finished shoe, illustrating the contour and shape of the rear quarter.

Figures 9 and 10 illustrate the application of a work strip to the outer quarter blank to facilitate subsequent lasting of the same.

Figure 11 is a fragmentary side elevation of the outer quarter folded upon itself, and with the work strip stitched thereto, and

Figure 12 is a fragmentary side elevation illustrating the quarter and work strip after lasting.

Referring now more particularly to the accompanying drawings, the present invention follows to a certain extent conventional shoe structure, in that the rear quarter A is secured to a vamp B in the usual manner, as best shown in Figure 4, the primary distinc-

tion residing in the fact that the rear quarter is formed from a single blank of material, thus eliminating the usual seam at the rear of the heel.

6 In the construction of a shoe, in accordance with the present invention, the rear portion of the upper comprises a quarter designated by the numeral 1, formed from a single blank of leather and comprising an intermediate portion 2, terminating in the flaps 3, which receive the usual eyelets 4, or other fastening devices, as indicated in dotted lines in

10 Figure 4, it being understood that the present illustration of the invention pertains to a blucher type shoe. However, the invention is applicable to various other styles, as the same resides primarily in forming the rear quarter from a single blank of material eliminating the rear seam.

20 In the construction of the shoe, the rear portion of the upper follows conventional design, in that a quarter lining 5, preferably formed from a soft, pliable blank of leather, is also provided. Furthermore, the usual 25 heel counter 6 is employed between the quarter 1 and the lining 5. In addition to the foregoing, an intermediate strip 7 is positioned between the quarter and lining, the strip 7 being formed from soft cushioning 30 material, preferably double-nap flannel, or similar fabric.

It is the common practice, in Goodyear welt shoes, to inseam the upper and welt to the insole from the heel forward, while the 25 upper at the heel is turned under and tacked, the tacks, which project through the insole, being turned over and covered by a suitable heel pad or lining. In the present structure, tacks are entirely eliminated, and the rear quarter, as well as the vamp, are secured to the inner sole 8 by inseam stitching 9, as best shown in Figure 7.

From the foregoing explanation it will be readily seen that an exceedingly inexpensive, durable and neat appearing shoe structure has been provided, which not only eliminates all of the objections to conventional seamed quarters, but materially improves the appearance of the shoe.

50 Other advantages will be quite obvious, in that a shoe constructed with a quarter, as heretofore described, adds materially to the comfort of the wearer, and entirely eliminates the possibilities of tearing or ripping, which 55 occurs where stitched rear quarters are employed. Also, a material saving on hosiery results, as there are no seams at the heel, where the greatest wear usually takes place, to rub the hose at that point. Furthermore, 60 the elimination of the back-seam enables the leather to be drawn closely to the last, resulting in a snugger fit of the heel, as no seam occurs to space the quarter from the foot.

As heretofore explained, considerable difficulty has been encountered in the process

of manufacture of a shoe having a one-piece rear quarter, due to the fact that it has been practically impossible to properly shape the quarter for snug engagement with the foot, and at the same time eliminate excessive bunching and accumulation of material at the heel seat. Therefore, one of the important features of the present invention resides in the highly novel method of assembling the parts comprising the rear quarter 75 of the upper.

Considering the method of manufacture, as exemplified in the successive figures of the drawings, it will be noted, as best shown in Figures 1 and 2, that the shape of the quarter 1, and the quarter line 5, differ slightly, particularly with reference to the connecting edges, the lower edge 10 of the quarter being more arcuate in contour than the lower edge 11 of the quarter lining. Therefore, in stitching the edges 10 and 11 together, as well as the edges of the lace tabs 3 and 7', it is necessary for the operator to aline the edges of the quarter and blank at a starting point, and thereafter crowd the material to aline the connecting edges of both blanks as the same are secured together with the stitching 12, to produce a completed quarter, as illustrated in Figure 3.

Due to the crowding of the quarter blank during the stitching operation, and the fact that the quarter blank is more arcuate in contour than the quarter lining, the quarter will have a tendency to bulge outwardly, as shown in Figure 3. The quarter and lining are then secured to the vamp B by stitching around the acute edges 13 of both the quarter and quarter lining, as illustrated in Figure 4, the vamp being disposed between the quarter and quarter lining. Here it will be readily understood that the intermediate padding strip 7 is secured to the inner face of the quarter prior to the stitching of the quarter and lining, the intermediate strip conforming in shape to the quarter. A heel counter 6 is then positioned between the lining and rear quarter, as best shown in Figure 7, the counter being formed of relatively stiff leather, composition, or the like, and having its upper and lower edges tapered off to provide relatively thin edges, thus providing an extremely rigid counter, and at the same time eliminating an abrupt ridge in the finished shoe at the top edge of the counter.

Contrary to the usual practice, a flat 120 counter is employed, the same being mulled prior to lasting, which results in the counter snugly conforming to the shape of the last as the same dries out. If desired, the relatively thin lower edge of the counter may be 125 slashed at spaced intervals to eliminate puckers, as the same is drawn over the heel seat.

The thin lower edge of the counter permits the same to be more easily worked in the lasting and inseaming operations.

After the upper has been assembled in the foregoing manner, the same is then lasted over the last 1 the insole 8 having been previously tacked to the last in the usual manner. The bottom of the upper is then drawn over the insole in the customary manner, and in addition to the usual tacks for holding the same, prior to the inseaming operation, a retaining wire 15 is secured to the last by tacks 16, and serves to draw the excess material of the quarter smoothly over the heel seat, as illustrated in Figure 6, and securely retain the same until the welt 17 and the completed upper are secured to the lip 8' of the insole 15 by the stitches 9. The wire 15 is then removed, and the projecting puckered edges of the upper are then trimmed off in the usual manner, after which a filler is applied to the insole, and an outsole 18 is stitched to 20 the welt, it being understood that the Goodyear welt extends around the entire periphery of the shoe, including the heel seat.

By the foregoing process it is possible to entirely eliminate lasting tacks commonly used in shoes. In all other construction it is necessary to temporarily tack the back of the quarters to the last when assembling the upper to the sole. By the present method, the quarter lining, which is of light pliable leather, is sprung over the last as the quarter is drawn over the heel seat, the quarter, counter and lining then being securely retained by the wire 15, thus eliminating the necessity of tacking the quarter, which is objectionable 35 because of the unsightly tack-holes resulting in the finished product, and providing a decided improvement in the appearance of the shoe.

While the foregoing method is exclusively employed in the majority of instances, some difficulty has been experienced in working or lasting seamless quarters formed from various leathers which are exceedingly stiff, as, for instance, patent leather, and therefore to facilitate the lasting operation in such cases, and at the same time insure smooth, unwrinkled engagement of the quarter around the heel seat, it is contemplated to utilize a work strip 17', as illustrated in Figures 9 to 12, inclusive.

As will be noted in Figure 9, the lower edge of the quarter 1 is inclined upwardly from a medial point, while the work strip 17' is normally straight. However, in stitching the work strip to the quarter, as illustrated in Figure 10, the same is crowded to follow the contour of the edge of the quarter, which causes it to assume a slightly arcuate concave shape that is partially imposed upon the lower edge of the quarter. Thus it may well be said that the work strip, due to springing the same during attachment of the quarter, will start the deside shaping of the lower edge of the quarter over the heel seat of the last, in addition to providing added material to assist in the lasting operation. In practice, it has been

found that the foregoing structure readily enables the operator to smoothly last the quarter in the usual manner, regardless of the stiffness or characteristics of the leather employed, eliminating the necessity of working out creases or wrinkles that might otherwise occur.

The remaining operations in completing the shoe are similar to those heretofore described, it being obvious that the work strip is trimmed off with the remaining excess material, subsequent to inseaming the welt and quarter to the insole.

While the drawings and description are directed to a truly seamless one-piece quarter, it is to be fully understood that the same is intended to include any structure of quarter in which the seam at the rear is eliminated. For instance, some oxfords may have foxing stitched to the rear quarter for the purpose of ornamentation. Other structures may be provided with straps extending around the quarter and stitched thereto. However, in all such structures the back seam is eliminated and the principles of the present invention are applied, particularly as regards the difference in configuration between the ultimate outer quarter and the quarter lining, and in the method of lasting and finishing of the shoe. Therefore, in referring to a one-piece or seamless rear quarter, it is to be fully understood that the same relates to, and includes, backs of any shape or design, in which the usual rear seam is eliminated.

From the foregoing explanation, it will be readily appreciated that a highly improved shoe structure and method of manufacture has been devised, which not only adds materially to the neatness and attractiveness in the appearance of the shoe, and its durability, but also results in added comfort to the wearer, as there are no objectionable seams at the heel to rub or damage tender feet, or cause undue wear on hosiery. The difference in contour and the spring of the quarter and quarter lining to space the same, as illustrated in Figure 4, compensate for insertion of the counter, and subsequent shaping of the quarter on the last, thus resulting in a snug, comfortable fit of the quarter surrounding the ankle, as illustrated in Figure 8, which prevents slipping at the heel, with resultant discomfort to the wearer.

I claim:—

1. In a shoe upper assembly, a seamless rear quarter comprising a one-piece outer quarter and a one-piece quarter lining, said outer quarter and quarter lining being of different blank configurations when in flat form with the upper edge of the outer quarter formed in a greater curvature than the lining, and stitches securing the quarter and lining together along their upper edges whereby to cause their lower edges to flare apart for reception of a heel counter and to cause the

quarter lining to snugly and smoothly hug the last and outer quarter to smoothly shape itself around the heel and under the heel seat.

2. In a welt shoe, a seamless rear quarter comprising a one-piece outer quarter and a one-piece quarter lining, said outer quarter and quarter lining being of different blank configurations when in flat form with the upper edge of the outer quarter formed on a greater curvature than the lining, and stitches securing the outer quarter and lining together along their upper edges whereby to cause their lower edges to flare apart for reception of a heel counter and to cause the quarter lining to snugly and smoothly hug the last and the outer quarter to smoothly shape itself around the heel and under the heel seat, an insole, and a Goodyear welt, said rear quarter and welt being stitched to said insole around the heel seat.

3. In a shoe upper assembly, a seamless rear quarter comprising a one-piece outer quarter and a one-piece quarter lining, said outer quarter and quarter lining being of different blank configurations when in flat form with the upper edge of the outer quarter formed on a greater curvature than the lining, and stitches securing the outer quarter and lining together along their upper edges whereby to cause their lower edges to flare, a normally flat heel counter positioned between said outer quarter and quarter lining, an intermediate strip of soft fabric conforming in contour to the outer quarter and secured between the said outer quarter and quarter lining, whereby the quarter lining snugly engages the last, and the outer quarter smoothly shapes itself around the heel and under the heel seat.

4. In a welt shoe, a seamless rear quarter comprising a one-piece outer quarter and a one-piece quarter lining, said outer quarter and quarter lining being of different blank configurations when in flat form with the upper edge of the outer quarter formed on a greater curvature than the lining, and stitches securing the outer quarter and lining together along their upper edges whereby to cause their lower edges to be normally spaced apart, a normally flat heel counter positioned between said outer quarter and quarter lining, an intermediate strip of soft fabric conforming in contour to the outer quarter and secured between said quarter and quarter lining, an insole, and a welt strip, said rear quarter, heel counter and welt being stitched to said insole around the heel seat.

5. The method of constructing a seamless rear quarter for shoes comprising forming an outer quarter and quarter lining from single blanks of different configurations with the upper edge of the quarter having a greater curvature than the upper edge of the lining, and stitching the blanks together at their upper edges and simultaneously crowding the

material to aline said edges to create a flare between the lower edges of said blanks.

6. The method of constructing a seamless rear quarter for shoes comprising forming an outer quarter and quarter lining from blanks of different configurations with the upper edge of the outer quarter formed on a greater curvature than the upper edge of the lining, stitching a work strip to the lower edge of the outer quarter and simultaneously crowding or bending the work strip to give the same a slightly concave arcuate shape, and stitching the blanks together at their upper edges and simultaneously crowding the material to aline said edges to create a flare

7. The method of constructing a seamless rear quarter for shoes comprising forming an outer quarter and quarter lining from blanks of different configurations with the upper edge of the outer quarter formed on a greater curvature than the quarter lining, stitching a straight work strip to the lower edge of the outer quarter and simultaneously curving the work strip to give the same a slightly concave arcuate shape, and stitching the blanks together at their upper edges and simultaneously crowding the material to aline said edges to create a flare between the lower edges of the blanks.
